FREDERICK M. BOWERS, OF CHESTER, PENNSYLVANIA

WELDER'S SHIELD

Application filed January 16, 1930. Serial No. 421,113.

This invention relates to a helmet and particularly to what is commonly known in the art as a welder's helmet or a shield used by welders for protecting the face and head from a welding arc.

It has been the practice heretofore in building welders' shields to form the visor or glass retainers of a metal stamping or to fabricate same from metal parts.

With metal stampings it is possible for the wearer to receive a shock should his face come in contact with the object on which he is working.

An example of this would be where the wearer is working on the inside of a metal container, such as a tank, steam boiler, etc., or among the working parts of a locomotive.

It is also common practice for a welder to weld the underside of an electric railroad track by lying on his side or back near the track in order to perform his work.

The object of this invention is to provide an improved welder's shield.

Another object is to provide a welder's shield free from danger to the wearer.

A further object is to provide a welder's shield wherein the visor frame is composed of electrical non-conducting material.

Still another object of the invention is to provide a welder's shield in which no metal parts pass from the outside to the inside of the same.

Another object of the invention is to provide a shield wherein the visor frame is protected from coming in contact with objects which might damage or injure the same.

According to the invention the shield has a visor opening at the rear of walls receding from the front of the shield, a visor frame formed of electrical non-conducting material, means for removably securing the visor frame in the shield whereby no metal parts extend from the outside to the inside of said shield.

The drawing illustrates an embodiment of the invention and the views therein are as follows:

Figure 1 is a vertical sectional view of a shield showing my improved visor frame and visor mounted thereon,

Figure 2 is a rear view of the visor and frame, looking in the direction of the arrow A in Figure 1, and with the greater part of the shield broken away,

Figure 3 is a top plan view of the separated parts of the visor frame.

Figure 4 is an end view of the same,

Figure 5 is a top plan view of the spring for holding the visor in the correct position in said frame, and

Figure 6 is a fragmentary front view of the inside frame part and shows the means of connecting the frame parts together.

The shield body 7, shown in section in Figure 1, is of the usual and customary contour and is provided with a recessed portion 8 consisting of the rearwardly sloping walls 9 terminating in a peripheral vertical flange 11.

This flange is located at a sufficient distance to the rear of the front wall 12 of the shield so that when the visor frame B is mounted on the frame 11 the front surface of the same will be considerably to the rear of the front wall 12 of the shield so that the same will not be accidentally injured, as is often the case when the frame protrudes beyond the front wall of the shield.

The shield frame comprises the inner part 13 and the outer part 14. The inner part 13 is rectangular in shape and has an opening 16 for permitting the wearer of the shield to look upon the work being conducted.

This part has a forwardly extending peripheral flange 17 and is provided at a point near the upper end of one side and the lower end of the other side with a recess 18 for receiving the curved lug 19 of the part 14.

In line with the center of each of these recesses there is a hole 21 extending through the peripheral flange 17 and a spring 22 is fastened to the side by means of rivets 23 at a point near its upper end and in line with the hole 21 is a pin 24 securely fastened in said spring and said spring terminates in an outwardly curled lip 26.

The outer part 14 is also generally rectangular and consists of an outer peripheral

flange 27 and a rearwardly extending leg 28 which fits snugly within the flange 17 on the inner part 13 and is also provided with an inwardly extending peripheral 5 flange 29 making the section taken at any place through the said member T-shape, as shown in Figure 1.

The rearwardly extending leg 28 is provided at the upper end at a point near the 10 top of its upper end on one side and at a point near its bottom on the other side with a curved lug 19 which extends in the same direction as said leg and said lugs are adapted, when the front part is assembled 15 with the inner part, to fit within the recesses 18 in said inner part.

When assembling the visor frame B, the glass 31 fits within the confines of the rearwardly extending peripheral leg 28 and the 20 pins 24 on the springs 22 are drawn outward so as to permit the curved lugs 19 to enter the recesses 18, whereupon the springs having been released, the pins will enter the holes 32 concentric with said curved lugs 25 and bind the parts firmly together and with the edge of the peripheral vertical flange 11 of the shield 7 securely gripped between the outer peripheral flange 27 on the outer part 14 and the peripheral flange 17 on the 30 inner part.

In order that the glass 31 be securely held against movement and firmly pressed against the inwardly extending flange 29 on the outer part 14, a rectangular spring member 33, shown in Figure 5, is inserted between said glass and the inner part 13, as shown in Figure 1, so that the curved upper and lower sides 34 of said spring, co-operating with the straight end portions 36, 35 will prevent any wobbling of the glass in the said frame.

The parts 13 and 14 are formed of electrical non-conducting material, such for instance as bakelite, and no metal parts whatsoever are located on the outer surface of the shield thereby preventing the transmission of any electric current through said shield to the person of the wearer.

Of course, the shield illustrated may be modified and changed in various ways without departing from the invention herein set forth and hereafter claimed.

The invention is hereby claimed as follows:

1. A welder's shield having an inwardly extending recess and a hole in the material of said recess providing vertical flanges, a rectangular visor frame composed of inner and outer parts slidably engaging to embrace said vertical flanges, means on the inner side of said shield for releasably securing said parts together, a glass in said frame and rectangular tension means held by said inner and outer parts for securing the same 65 against movement.

2. A visor frame comprising a rectangular outer part T-shaped in section, a rectangular inner part angular in section, the leg of the T-shaped section of said outer part slidably fitting within the peripheral angular section of the inner part, and means for securing said parts together. 70

3. A visor frame comprising a rectangular outer part T-shaped in section, a rectangular inner part angular in section, the leg of the T-shaped section of said outer part fitting within the peripheral angular section of the inner part, lugs on said outer part, recesses on said inner part for receiving said lugs, and means on said inner part for securing the parts together. 75

4. A visor frame comprising a rectangular outer part T-shaped in section, a rectangular inner part angular in section, the leg of the T-shaped section of said outer part fitting within the peripheral angular section of the inner part, lugs on said outer part, recesses on said inner part for receiving said lugs, holes in proximity to the lugs in said outer part, and spring pressed pins 80 carried by said inner part for fitting within said holes to secure the parts together. 85

5. A visor frame comprising a rectangular outer part T-shaped in section, a rectangular inner part angular in section, the leg of the T-shaped section of said outer part slidably fitting within peripheral angular section of the inner part, and leaf springs on the inner part each carrying a pin, said outer part having recesses for receiving said pins to releasably hold the parts together. 90

6. A visor, comprising an arcuate body, a section of which departs from said arcature and coincides substantially with a plane, said plane section being provided with an opening forming marginal flanges in planer unity, a transparent member approximately co-planar with the flanges, and inner and outer frame members coacting 100 with each other to clamp both the transparent sheet and the flanges therebetween. 105

7. A visor, comprising an arcuate body, a section of which departs from said arcature and coincides substantially with a plane, said plane section being provided with an opening forming marginal flanges in planer unity, a transparent member approximately co-planar with the flanges, and inner and outer frame members having lateral extensions coacting with each other to clamp both the transparent sheet and the flanges therebetween. 115

8. A visor, comprising an arcuate body, a section of which departs from said arcature and coincides substantially with a plane, said plane section being provided with an opening forming marginal flanges in planer unity, a transparent member approximately co-planar with the flanges, inner and outer 120

frame members coacting with each other to clamp both the transparent sheet and the flanges therebetween, and means to lock the members in clamping position.

5 9. A visor, comprising an arcuate body, a section of which departs from said arcature and coincides substantially with a plane, said plane section being provided with an opening forming marginal flanges in planer

10 unity, a transparent member approximately co-planar with the flanges, inner and outer frame members having lateral extensions coacting with each other to clamp both the transparent sheet and the flanges therebe-

15 tween, and means to lock the members in clamping position.

10. A visor, comprising an arcuate body, a section of which departs from said arcature and coincides substantially with a plane,

20 said plane section being provided with an opening forming marginal flanges in planer unity, a transparent member approximately co-planar with the flanges, inner and outer

25 frame members provided with registrable perforations coacting with each other to clamp both the transparent sheet and the flanges therebetween, and pins inserted through the perforations locking the frame members together.

30 11. A visor, comprising an arcuate body, a section of which departs from said arcature and coincides substantially with a plane, said plane section being provided with an opening forming marginal flanges in planer

35 unity, a transparent member approximately co-planar with the flanges, inner and outer frame members provided with registrable perforations coacting with each other to clamp both the transparent sheet and the flanges therebe-

40 tween, and spring pressed pins inserted through the perforations locking the frame members together.

12. A visor, comprising an arcuate body, a section of which departs from said arc-

45 ture and coincides substantially with a plane, said plane section being provided with an

opening forming marginal flanges in planer unity, a transparent member approximately co-planar with the flanges, inner and outer frame members having lateral extensions provided with registrable perforations co- 70 acting with each other to clamp both the transparent sheet and the flanges therebetween, and means to lock the members in clamping position.

13. A visor, comprising an arcuate body, a section of which departs from said arcature and coincides substantially with a plane, said plane section being provided with an opening forming marginal flanges in planer

75 unity, a transparent member approximately planar with the flanges, inner and outer frame members having lateral extensions provided with registrable perforations and coacting with each other to clamp both the transparent sheet and the flanges therebe-

80 tween, and pins inserted through the perforations locking the frame members together.

14. A visor, comprising an arcuate body, a section of which departs from said arcature and coincides substantially with a plane, said plane section being provided with an opening forming marginal flanges in planer

85 unity, a transparent member approximately planar with the flanges, inner and outer frame members having lateral extensions provided with registrable perforations and coacting with each other to clamp both the transparent sheet and the flanges therebe-

90 tween, and spring pressed pins inserted through the perforations locking the frame members together.

15. A visor frame comprising a rectangular part T-shaped in section, a rectangular

95 part angular in section, the leg of the T-shaped section of said first part slidably fitting within the peripheral angular section of the second part, and means for securing

100 said parts together.
